UNITED STATES PATENT OFFICE

126,663

DESIGN FOR A MOTOR-TRICYCLE

Emmett A. Niblack, Biloxi, Miss.

Application December 14, 1939, Serial No. 88,893

Term of patent 14 years

To all whom it may concern:

Be it known that I, Emmett A. Niblack, a citizen of the United States and a resident of Biloxi, in the county of Harrison and State of Mississippi, have invented a new, original, and ornamental Design for a Motor-Tricycle, of which the following is a specification, reference being had to the accompanying drawing, forming a part thereof, in which:

Fig. 1 is a front perspective view of a motor-tricycle showing my new design;

Fig. 2 is a rear perspective view; and
Fig. 3 is a top perspective view.

The characteristic features of my design for a motor-tricycle reside in the portions shown in full lines in the drawing.

I claim:

The ornamental design for a motor-tricycle, as shown and described.

EMMETT A. NIBLACK.
